PAPER DELIVERY MECHANISM

George Schaefer, Jr., Flushing, N. Y., assignor to
 Sanitary Public Service Corporation, New York,
 N. Y., a corporation of Delaware

Application December 19, 1933, Serial No. 703,099

15 Claims. (Cl. 164—68)

The present invention relates to paper delivery mechanism and is more particularly directed toward paper delivery mechanism suitable for use with vending and dispensing machines wherein articles such as paper towels, toilet seat covers, and the like are made out of a roll of paper and vended or dispensed to the customer.

Machines of this nature have a cycle of operations according to which an article is completed each time the mechanism is released and manually operated. After the completion of the formation of the article, the machine stops automatically. These articles are comparatively large and according to the most convenient method of dispensing, the formed article is passed downwardly out of the machine so that the user may remove it. To keep the article from dropping away from the machine the article is incompletely severed from the web.

20 Seat cover making and vending machines are shown in Stahly Patent No. 1,840,266, dated January 5, 1932, and Doane Patent No. 1,844,684, dated February 9, 1932.

It has been found that when the article is allowed to pass down from the machine as the paper progresses through the machine, a user, unacquainted with the functioning of the machine, is likely to take hold of the oncoming article as soon as it appears and try to pull it from the machine. This destroys the article being formed and impairs the operation of the machine, for the user or customer may not complete the turning of the handle so as to complete the cycle.

35 The present invention contemplates delivery mechanism for machines of this character, so designed that it is necessary for the customer to complete the cycle of operations, whereby the toilet seat cover or towel is formed, before the formed article is accessible for removal from the machine. Accordingly, the machine is provided with a chamber or chute to receive the formed article while it is being made, this chamber being closed except at the end of the cycle 45 when it is automatically opened to allow the article to fall out. It can then be manually removed. This makes it necessary for one to complete turning of the handle to the stop position before obtaining either the toilet seat cover or the towel.

Inasmuch as these articles are too long to permit having a chute of a length greater than the article, it is necessary to have the articles folded up on top of the bottom of the closed chamber.

55 The present invention contemplates that the

chamber shall have front and rear walls which confine the paper so that it cannot escape by wrapping around the pressure or guide rollers.

Other and further objects of the invention will appear as the description proceeds.

5 The accompanying drawings show, for purposes of illustrating the present invention, one of the many embodiments in which the invention may take form together with modifications of certain parts, it being understood that the drawings are illustrative of the invention rather than limiting the same. In these drawings:

Fig. 1 is a vertical sectional view through a machine embodying the paper delivery mechanism, the door at the bottom of the chamber being open;

Fig. 2 is a perspective view of the delivery mechanism on a large scale;

Fig. 3 is a fragmentary top plan view of a portion of this mechanism;

Fig. 4 is a fragmentary sectional view similar to Fig. 1, showing the chamber closed;

Fig. 5 is a fragmentary front elevational view of the machine showing an article completed and suspended ready for removal;

Fig. 6 is an end view of the machine showing a form of stop and release mechanism for controlling the beginning and ending of the cycle of operations, the parts being in the stop position;

Fig. 7 is a view similar to Fig. 6, showing the release of the stop mechanism;

Fig. 8 is a vertical sectional view through the stop mechanism of Figs. 6 and 7;

Fig. 9 is a fragmentary elevational view 35 through a portion of the stop mechanism; and

Fig. 10 is a fragmentary view similar to Fig. 1, illustrating a modified form of door operating means for the chute.

The female and male rollers of the machine are indicated at 20 and 21, respectively. The roller 20 is half the diameter of the roller 21 and these two rollers are provided with cooperative grooves 20a and knives 21a for forming a seat cover or towel. The shape of these knives and grooves may be the same as that shown in either of the patents above referred to. A gear train, indicated at 22, 23, 24, 25, times these two rollers so that they operate in unison.

A web roll is indicated at W.

The web w passes about a guide roll 26, the female roller 20, and between the knives and grooves, after which it passes about a series of toothed rubber drawing rollers 27. These rollers

- are carried on a shaft 28 driven by a gear 29 which is in mesh with a gear 30 carried by the female roller 20. The rollers 20 and 27 provide drawing rollers which draw the paper through the machine. The paper is delivered downwardly past the front face of the pressure rollers 27 by delivery rolls indicated at 31. These rolls are carried on a shaft 32 provided with a gear 33 in mesh with a gear 34 carried on shaft 28.
- 10 The gear 34 is slightly larger in diameter than the gear 33, so that the shaft 32 is driven at a higher rotary speed than the shaft 28. In this way the surface speed of the rolls 31 may be made slightly greater than the pressure rollers 27, so that there is always a tendency to force the paper down instead of permitting it to pass upwardly between the rollers 20 and 31.
- 15 The machine is operated by a hand crank indicated at 35, secured to the gears 22 and 30, and the female roller 20 in any convenient manner. The crank shaft 35 also carries a locking lug 36 which in turn revolvably supports a thin disc 37. This disc has a limited movement by reason of the pin and slot connection, indicated at 38, 39. It has a laterally bent ear indicated at 40 and is notched in front of this ear as indicated at 40'. It is urged in a clockwise direction by a coiled spring 41 interconnecting the lug 36 and disc 37.
- 20 A selector lever 42 is mounted to rock about the crank 35 and is held in the position indicated in Fig. 6 by a coiled spring 43. This lever has a notch indicated at 44 (Fig. 9) and laterally extending flanges 45 and 46. The notch 44 is adapted to receive the nose 47 of a stop lever 48 pivoted at 49, and urged counter-clockwise by a spring 50. The upper left end of this lever has a shoulder 51 which is adapted to engage a shoulder 52 of the locking lug 36 and the lateral extension 40 of the disc 37. When the parts are in the full line position of Fig. 6, turning the hand crank clockwise is prevented.
- 25 Should one raise or lower the selector lever 42, it will be rocked about the axis of the crank 35, and one or the other of the flanges 45 or 46 will engage the nose 47 of the stop lever 48, thereby shifting it to the position indicated in Fig. 7. This brings the shoulder 51 above the lateral extension 40 on disc 37 and allows the spring 41 to shift this disc on the locking lug so that the edge of the disc 37 passes under the abutment 51. The selector lever may now be released and it will turn back to the full line position of Fig. 6. The stop lever 48, however, is held against movement and the crank may now be turned in a clockwise direction to effect two revolutions of the female roller and one revolution of the male roller.
- 30 The male roll carries a cam 53 which is adapted to engage an inwardly extending member 54 carried on the lower end of the stop lever 48 so as to hold this lever in the elevated position at the proper time. At the time when the notch 40' of the disc 37 is opposite the stop lever on the latter part of the first revolution of the crank handle, the cam 53 is in the dot and dash line position of Fig. 7 and holds the stop lever against the tension of the spring 50 and prevents the upper left part of the stop lever from lowering. After the cam 53 is passed beyond the extension 54, the stop lever is released, so that the spring 50 may press the left end of the lever against the edge of the disc 37. When the end of the cycle 35 is approached, the stop lever drops into notch 40'

in front of the shoulders 52 and 40 so as to engage them and stop the crank.

The end of the male cylinder 21, opposite the handle and stop control mechanism, is provided with a cam plate 60 indicated in dotted lines in Fig. 1. This cam plate cooperates with a lever 61 pivoted at 62 and connected by a link 63 with a door 64. This door is formed out of sheet metal, has a bottom portion 65, upwardly extending members 66, and end flanges 67. These end flanges are pivoted about a shaft 68 and the upward extensions 66 are bent to pass part-way about this shaft. The cam 60 is provided with a notch 69 which is adapted to receive a projection 70 carried on the lever 61. This notch is positioned on the male roll so that it comes opposite the extension on the lever just prior to the functioning of the stop mechanism to stop the turning of the machine. This allows the door to open under the influence of gravity and to shift the parts into the full line position of Fig. 1. A spring 62' may be added to facilitate the opening, if desired.

As soon as the machine has started to make a new article, the notch 69 operates the lever 61 to close the door 64, placing it in the position shown in Fig. 4. The door 64 is across the bottom of a delivery chute having a front wall 71 in the form of a vertical sheet metal plate having upward extensions 72 which pass about the shaft 32 between the rollers 31. This metal plate makes it impossible for the paper to be forced forwardly out of the machine.

To form the rear wall of the chute, belts 73 are employed. These belts are passed about the shaft 28 between the toothed rubber rollers 27 and about the shaft 68. These belts are preferably made of rubber and are tight enough to be driven by the shaft 28. Inasmuch as they extend inwardly beyond the surface of the pressure rollers 27, they engage the paper and prevent the paper from wrapping around the pressure rollers.

From the foregoing it will be apparent that when the cycle of operations is completed, the door 64 is opened, and as soon as one starts to turn the crank the door 64 is immediately closed. This will cause the paper to pile up on top of the door 64 somewhat as indicated in Fig. 4. The paper cannot pass out of the chute formed by the plate 71 and belt 73. As soon as the end of the cycle 50 is reached, the cam 60 brings about an opening of the door 64 so that the completed article drops out, somewhat as indicated in Fig. 5, where one can take hold of it and remove it from the machine.

It will be understood that the configuration of the male and female rollers may be varied according to the design of the article which is to be made, and that this design is preferably one which incompletely severs the article so that the article will not drop free of the machine.

In the form of construction shown in Fig. 10, the door 80 is similar to the door 64. It is urged toward closed position by a spring 81 and is opened by a cam 82 carried by the male roll and engaging two toggle levers, indicated at 83 and 84, at the end of the cycle. In this form of construction the door may be manually opened whenever desired by pressing downwardly on the front edge to tension the spring, while in the form of construction shown in Figs. 1 and 2 the door is held tightly closed at all times except when it is allowed to open by the mechanism.

It will also be understood that various forms of stop and release mechanism may be employed to 75

control the cycle of operations, the one shown herein being illustrative of a suitable structure for this purpose and forming the subject matter of another application.

It is obvious that the invention may be embodied in many forms and constructions within the scope of the claims, and I wish it to be understood that the particular form shown is but one of the many forms. Various modifications and changes being possible, I do not otherwise limit myself in any way with respect thereto.

What is claimed is:

1. A machine having a cycle of operations for severing a web of paper to form paper articles one at a time, including male and female rollers meshing together and having severing devices which cut the web to form the article to shape without completely severing the same, a pressure roller disposed to grip the entire width of the paper after severing to thereby hold the formed but incompletely severed article suspended, manually releasable stop mechanism for stopping the machine with the completed article passed beyond the pressure roller, a delivery chute having front and rear walls confining the paper after it passes by the pressure roller, a movable door across the bottom of the chute, and door operating means effective for keeping the door closed except at the end of the cycle whereby the article being formed is confined in the chute above the door during formation and for opening it at the end of the cycle to allow the article to drop out of the chute.

2. A machine as claimed in claim 1, wherein the door operating means includes a cam movable with the male roller, and a spring pressed lever bearing on the cam and connected with the door.

3. A machine as claimed in claim 1, wherein the door operating means includes a spring for holding the door closed, and a cam and follower for forcing the door open.

4. A machine as claimed in claim 1, wherein the rear wall of the delivery chute includes vertically extending belts extending about small diameter portions of the pressure roll and a lower shaft, and the door is hinged about said shaft and has extensions passing between the belts whereby escape of paper rearwardly is prevented.

5. A machine as claimed in claim 1, wherein the front wall of the delivery chute includes a stationary plate extending from above the axis of the pressure roll down to the front edge of the door when closed.

6. The combination with a machine having a cycle of operations for forming a paper article out of a web and dispensing the formed article incompletely severed from the web so that it may hang suspended for manual removal, of stop means for insuring that the cycle is completed before the article becomes available for such manual removal, comprising a chute into which the article is passed as it is fed from the severing mechanism, a chute closer across the bottom of the chute, and chute closer operating means which opens the chute at the end of the cycle to drop the article down, and which closes the chute when the cycle is again commenced.

7. A paper article forming machine as claimed in claim 6, wherein the stop means and chute closer operating means are independent.

8. In a web handling machine, a pair of drawing rollers between which a web is drawn, one roller having small diameter portions not in contact with the other and being so positioned rela-

tive to the other that the web passes about the upper portion thereof under the influence of gravity, and belts driven by the small diameter portions to prevent the web material from wrapping itself about that drawing roller, so that it must pass downwardly free of said roller.

9. In a web handling machine, a pair of drawing rollers one above the other for drawing a web between them and normally feeding it downwardly from the lower roller, a delivery roll in front of the lower roller and close to the first roller, means to drive the delivery roll at a surface speed in excess of the surface speed of the rollers and web, whereby the web is prevented from passing up about the upper roller, and means preventing the web from wrapping itself about the delivery roll.

10. In a web handling machine, a pair of drawing rollers one above the other for drawing a web between them and normally feeding it downwardly from the lower roller, a delivery roll in front of the lower roller and close to the first roller, means to drive the delivery roll at a surface speed in excess of the surface speed of the rollers and web, whereby the web is prevented from passing up about the upper roller, the delivery roll having small diameter portions and stationary guides extending toward the small diameter portions between the larger diameter portions for intercepting the web and preventing its wrapping about the delivery roll.

11. In a web handling machine, a pair of drawing rollers one above the other for drawing a web between them and normally feeding it downwardly from the lower roller, belts driven by the lower roller for preventing the material from wrapping about that roller, a delivery roll in front of the lower roller and close to the first roller, means to drive the delivery roll at a surface speed in excess of the surface speed of the rollers and web, whereby the web is prevented from passing about the upper roller, and means for preventing the web from wrapping itself about the delivery roll.

12. In a web handling machine, a pair of drawing rollers one above the other for drawing a web between them and normally feeding it downwardly from the lower roller, belts driven by the lower roller for preventing the material from wrapping about that roller, a delivery roll in front of the lower roller and close to the first roller, means to drive the delivery roll at a surface speed in excess of the surface speed of the rollers and web, whereby the web is prevented from passing about the upper roller, the delivery roll having small diameter portions, and stationary guides extending toward the small diameter portions between the larger diameter portions for intercepting the web and preventing its wrapping about the delivery roll.

13. A web handling mechanism having a pair of drawing rolls past the second of which the web is delivered, a driven guide roll having a surface speed in excess of the drawing rollers for preventing the web from passing about the first of the pair of drawing rollers, and chute forming means comprising belts driven by the second drawing roll, and a stationary member having portions which project across the effective surfaces of the take off roll.

14. A web handling mechanism having a pair of drawing rolls past the second of which the web is delivered, a driven guide roll having a surface speed in excess of the drawing rollers for preventing the web from passing about the first of the

pair of drawing rollers, and chute forming means comprising belts driven by the second drawing roll, a stationary member having portions which project across the effective surfaces of the guide roll, and a door for closing the bottom of the chute.

15. A web handling mechanism having a pair of drawing rolls past the second of which the web is delivered, a driven guide roll having a surface speed in excess of the drawing rollers for pre-

venting the web from passing about the first of the pair of drawing rollers, chute forming means comprising belts driven by the second drawing roll, a stationary member having portions which project across the effective surfaces of the guide roll, and a chute closing door across the bottom of the chute, the door having extensions passing between the belts.

GEORGE SCHAEFER, Jr.
